UNITED STATES PATENT OFFICE

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK

ENGINE STARTER

Application filed January 4, 1923. Serial No. 610,672.

My invention has relation to means for starting or cranking an engine such as an internal combustion engine, and more particularly to that part of an engine starter system known as the drive or transmission which transmits the power of a prime mover such as an electric motor to a part or member of the engine to be started such as the fly-wheel thereof. The object of my invention is to provide a simple and efficient drive or transmission which is capable of manual operation for engagement with the engine member and of automatic disengagement. My drive contains novel features of construction resulting in novel operations and results, which will be apparent from the description hereinafter given.

In the drawings, Figure 1 is an elevation, partly in section of an engine starter system embodying my invention, showing the parts in normal disengaged position; Fig. 2 a similar view but showing the parts in cranking position; Fig. 3 another similar view but showing the position of the parts with the engine started and the starting motor still rotating; Fig. 4 a sectional elevation of the drive or transmission as applied to the extended armature shaft of an electric motor; Fig. 5 a view similar to that of Fig. 4 but viewing the drive from a different angle; Fig. 6 an elevation of one end of the pinion; Fig. 7 a section on the line 7—7 of Fig. 6; Fig. 8 a cross section on the line 8—8 of Fig. 5; Fig. 9 an elevation of a starter system illustrating my invention embodied in a modified form of construction; Fig. 10 a sectional elevation of the modified form, showing the parts in normal disengaged position; Fig. 11 a similar view but showing the parts in the cranking position; Fig. 12 a similar view showing the parts in the position after starting the engine and with the shifter connection still in operated position and the motor still running; and Fig. 13 an end view of the pinion. For the purpose of a clear and definite disclosure of my invention, I have shown the same embodied in two structures, one being illustrated in Figs. 1 to 8 and the other in Figs. 9 to 13, but it will be understood that the same may be embodied in structures of

somewhat different formation and arrangement, without departing from the spirit and scope of my invention. It will also be understood that while I have shown my invention as applied to the so-called inboard type of drive the same may be applied to the outboard type of drive. Further it will be understood that while I have shown my invention embodied in that type of drive known as the direct drive, in which the drive is connected with the extended armature shaft of an electric motor, my invention is also applicable to the indirect drive in which the drive or transmission is connected with a countershaft driven by the armature shaft.

Referring to the particular embodiment of my invention as illustrated in Figs. 1 to 8, the prime mover is an electric motor 1 provided with an extended armature shaft 2. This motor is provided with a suitable switch 3 and its usual electrical connections.

The drive or transmission is formed as an assembly which is readily applied to and detachable from the extended armature shaft. This drive assembly comprises, in the present instance, a sleeve 4 secured to the armature shaft in a suitable manner as by means of a pin 5, and also comprises a hollow shaft 6 splined to the armature shaft by means of a longitudinal spline or splines 7 and provided at its middle portion with screw threads 8 and at its inner end with suitable stop means such as a nut 9. This screw shaft at its outer end is provided with or formed as an enlarged head 10 with a circumferential groove 11, to cooperate with the shifting means hereinafter described. It will be understood that the sleeve 4 is not essentially a separate element except where required for assembly purposes. It will be understood that the splines 7 instead of being formed or provided on the armature shaft itself may be carried by a separate sleeve secured to a plain armature shaft.

Upon the screw threaded portion of the shaft, there is mounted for longitudinal movement thereof and rotary movement therewith a driving member which is here in the form of a pinion 12. This pinion is adapted to mesh with the member of the engine to be

started which is here the fly-wheel 13 of an internal combustion engine.

Suitable means are provided in the screw shaft for holding the pinion in a retracted position with respect thereto as shown in Fig. 3. In the present instance, such means consist of a latch 14 adapted to cooperate with the pinion for the purpose stated. This latch is movable in a longitudinal slot 15 formed in the screw shaft and is pivoted intermediate its length by means of a pin 16. The latch is spring pressed downwardly as to its outer end by means of a plunger 17 backed up by a spring 18, which plunger and spring are located in a radial chamber 19 in the head 10. This chamber is closed at its outer end by the screw plug 20. The outer end of the latch, therefore, tends to move downwardly and its inner end upwardly to a position corresponding to the screw threads 8 to thereby engage with the longitudinal slot 21 formed in the bore of the pinion, as shown in Fig. 7. The tendency of the latch to assume said position is normally restrained by the surface 22 formed on the sleeve 4 with the result that when the drive is in normal disengaged position as shown in Figs. 1 and 4, the forward end of the latch is held in inoperative position, that is, entirely below the inside diameter of the screw threads 8. However, when the screw shaft is moved longitudinally inwardly so that the latch rides off of the sleeve 4, the spring pressed plunger 17 will force the outer end 35 of the latch inwardly and the forward end of the latch outwardly to operative position. When the screw shaft is shifted outwardly longitudinally, the outer curved end of the latch will ride up upon the beveled surface 40 23 and on to the surface 22 of the sleeve 4.

The screw threads are in the present instance provided with a long lead so that in case the pinion teeth do not register with the fly-wheel teeth, but such teeth should 45 abut end to end, the screw shaft will continue to move inwardly, notwithstanding the arrest of the longitudinal movement of the pinion, and such pinion will thereupon be moved slightly rotarily and will mesh with 50 the fly-wheel. The normal position of the pinion is its outward position as shown in Figs. 1, 2 and 4, at which time it is in contact with the stop nut 9, and such pinion is held in this normal position with a yielding pressure which in this instance is due to 55 a light coil compression spring 24, encircling the screw shaft and interposed between the pinion and the head 10 of such shaft.

For manually shifting the drive into engagement with the fly-wheel, I employ operating connections between a suitable plunger 25, operated by hand or foot, and the head 10 of the drive. As shown, these operating connections comprise a bell crank with one 60 arm 26 contacted by the plunger 25 and

adapted to contact and operate the button of the electric switch 3. This bell crank is here shown as pivoted at 27 upon a plate or bracket 28 which is secured to the frame of the motor 1, the bell crank being retained in normal position by means of the coil spring 29. The other arm 30 of the bell crank is connected by a rod 31 with a depending lever 32 pivoted stationarily at 33 and provided at its lower end with suitable rollers or antifriction devices. These rollers engage the groove 11 of the head 10 of the screw shaft and cause the shifting or reciprocation of such shaft or drive assembly in both directions.

Describing a cycle of operation and beginning with the parts in their normal position as shown in Fig. 1, the operator or driver depresses the plunger 25 against the tension of its return spring 35, thereby rocking the bell crank from the position shown in Fig. 1 to the position shown in Fig. 2. The screw shaft and pinion are now shifted inwardly and just as the pinion has been fully meshed with the fly-wheel, the plunger and bell crank cause a depression and actuation of the button of the switch 3, whereupon the electric motor is operated and the fly-wheel is rotated by the pinion. The torque is transmitted from the armature shaft through the splines 7, screw shaft 8 and thence to the pinion 12. The parts are now in the cranking position shown in Fig. 2, at which time the forward or inner end of the latch 14 is in its raised position coincident with the screw threads 8.

When the engine operates under its own power, the operator should release the plunger 25 with the result that the drive assembly and the operating connections will be restored to normal position. In such restoration of parts, the demeshing of the pinion from the fly-wheel is facilitated in an automatic manner by virtue of its threaded connection with the screw shaft. If the operator should fail to release the plunger 25 immediately upon the starting of the engine, the construction is such that no damage to the drive will result. In such event, the screw shaft will retain its operated or shifted position and the pinion will be automatically demeshed, whereupon the parts will have the position illustrated in Fig. 3. When the pinion is thus demeshed and screwed backwardly along the screw shaft and comes within the range of action of the latch 14, such latch will be engaged by the slot 21 in the pinion and such pinion and shaft will be held together for rotary movement in unison. As a result, the pinion is prevented from longitudinal movement with respect to the screw shaft and consequently even though the starting motor and the screw shaft are still rotating, it is impossible for the pinion to be advanced longitudinally into mesh again.

with the fly-wheel. When the operator then releases the plunger 51, the screw shaft will be shifted outwardly to normal position and when in such longitudinal position the surfaces 22 and 23 of the sleeve are presented to the outer end of the latch, such latch will be operated to release it from the pinion. The pinion is thereupon permitted to move spirally along the screw shaft and against the stop nut by reason of the provision of the compression spring 24, the lead of the threads 8 being such as to permit of such spiral action of the pinion when pressed in a longitudinal direction by the light spring 24.

In Figs. 9 to 13, I have shown a modified form of construction in which similar parts are designated by corresponding reference numerals. The construction is substantially the same as that previously described but the drive is applied to a vertically disposed electric motor that is to a motor whose armature shaft is arranged in a vertical position, the pinion or driving member of the drive in such case reciprocating with teeth on one face of the fly-wheel instead of the periphery thereof. The construction of the drive differs in the omission of the spring 24 whose function of holding the pinion yieldingly in a normal position, is performed by gravity.

Referring to the modified form of construction the electric motor 36 which is vertically disposed is supported in suitable manner, as for instance upon the internal combustion engine 37, being secured thereto by means of the bolts 38. The vertical armature shaft 39 is extended and depends below the motor. The motor is provided with the usual switch 40 and switch button 41, here shown on one side of the motor frame, and also with suitable electrical connections or circuits, not necessary to be shown.

The drive or transmission is an assembly which is mounted upon the extended armature shaft 39. As shown this drive is enclosed within casing 42 secured to and depending from the lower end of the motor frame, which casing has a side opening at its lower end at 43 in position to register with the circular rack of teeth 44 secured or formed upon the rear face of the engine member which is here the fly-wheel 45 of the engine. The armature shaft 39 extends the full length of the casing 42 and is journaled in the bearing 46 at the lower end of such casing. This shaft has three different diameters, forming three different portions, to-wit, a long outer portion 47, a rear portion or head 48 and an intermediate portion 49. At the junction of these two portions 48 and 49 there is a circumferential beveled portion 50.

The drive proper is readily attachable to and detachable from the armature shaft 39 and is driven thereby and also capable of a longitudinal movement thereon. The con-

struction and operation of this drive is substantially the same as the drive previously described, except that the gravity of the pinion takes the place of the compression spring 24 of the first described construction. However, in the present instance the manual or pedal operated connections are somewhat different. In the present instance I have shown a pedal operation but it will be understood that I use the term "manual" in the claims in its generic sense as including both manual and pedal operations.

As shown in Fig. 9 a plunger 51 extends through the floor board 52 of the automobile to which I have for convenience shown the starter system applied. This plunger reciprocates in the bearings 53 and 54 and is normally held upwardly pressed by the coil spring 55. It is provided with a radially extending arm 56 adapted to contact and operate the switch button 41 when such plunger is depressed by the operator or driver. This plunger is operatively connected by a yielding lost motion connection with a bell crank comprising an arm 57 loosely connected with the plunger and another arm 58 projecting into the casing 42 and operatively engaging the drive. This bell crank is pivoted at 59 to a bracket 60 extending from one side of the casing 42. A spring 61 is interposed between a collar 62 rigidly mounted on the plunger 51 and the arm 57 and acts as a part of the lost motion connection.

Describing a cycle of operation and beginning with the parts in their normal position shown in Figs. 9 and 10, the operator first depresses the plunger 51 thereby causing the shifter connections to shift the screw shaft downwardly upon the armature shaft, the pinion 20 being of course lowered at the same time. After the screw shaft has reached its lower limit of movement, the plunger 51, being permitted to move further by the spring 61 causes the contact arm 56 to operate the switch, thereby energizing the motor. Upon the rotation of the armature shaft, the screw shaft is rotated through its splined connection therewith and as the pinion is now in mesh with the teeth 44 of the flywheel as shown in Fig. 11 such flywheel is rotated and the engine is cranked.

When the engine starts on its own power, the operator should release the plunger 51, which will cause a retraction of the entire drive assembly, and the demeshing of the pinion will be facilitated by its threaded connection with the screw shaft, with the result that the pinion will be screwed backwardly or upwardly along the screw shaft in this demeshing operation. However, if the operator should fail to release the plunger 51, when the engine starts on its own power, no damage will result to the drive because of the provision of the catch mechanism which is adapted to hold the pinion 120

in retracted position in the same manner as hereinbefore described in respect to the first form of drive. The position of the parts under this condition is illustrated in Fig. 12. 5 Then when the operator finally releases the plunger 51, the drive assembly will be raised or moved upwardly by reason of the tension of the spring 55 which restores the parts to their normal position. In this upward 10 movement of the screw shaft, the upper end of the latch 14 will ride up on the beveled surface 50 and on to the enlargement 49 of the armature shaft, to the position shown in Fig. 10, thereby releasing the latch from 15 the pinion and permitting the latter to move spirally by gravity to the lower end of the screw threaded portion of the shaft and against the stop nut 9, thereby assuming the position shown in Fig. 10. It is understood 20 that the pinion is held slightly above the fly-wheel teeth as shown and in position for repetition of the cycle of operation above described.

In the event that the pinion teeth and the 25 fly-wheel teeth should not register when the screw shaft is lowered as described, the pinion will be arrested in its downward movement and the screw shaft, owing to the long lead of the threads, will continue to move 30 downwardly, relatively to the pinion, with the result that the pinion will be rotated slightly, which will cause register with the fly-wheel teeth.

I claim:

35 1. An engine starter drive comprising a rotatable shaft, a sleeve mounted to slide thereon and driven thereby, a driving member mounted upon the exterior of the sleeve for rotary movement therewith and for 40 longitudinal movement thereof, for engagement with a member of the engine to be started, means for bodily shifting the sleeve and driving member longitudinally on said shaft, and means for holding the driving 45 member in a disengaged position after being disengaged from the engine member, and means controlled by the position of the sleeve relative to the shaft for releasing said holding means.

50 2. An engine starter drive comprising a rotatable shaft, a sleeve mounted to slide thereon and driven thereby, a driving member mounted upon the exterior of the sleeve for rotary movement therewith and for 55 longitudinal movement thereof, for engagement with a member of the engine to be started, means for bodily shifting the sleeve and driving member longitudinally on said shaft, and means for holding the driving 60 member in a disengaged position after being disengaged from the engine member, said holding means comprising a latch mounted on the sleeve and adapted to engage said driving member and also cooperating with 65 the shaft.

3. An engine starter drive comprising a rotatable shaft, a sleeve mounted to slide thereon and driven thereby, a driving member mounted on the sleeve for rotary movement therewith and for longitudinal movement thereof for engagement with a member of the engine to be started, means for bodily shifting the sleeve and driving member longitudinally on said shaft, said sleeve having at one end means for stopping the longitudinal movement of the driving member in one direction, and the driving member being normally positioned against said stop means, and means movable with respect to the sleeve to operative or inoperative position and controlled by the position of the sleeve relative to the shaft for holding the driving member in retracted position on such sleeve. 70

4. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, the screw thread of the shaft having a long lead whereby longitudinal pressure on the pinion causes rotation thereof to produce register between such pinion and engine member, said pinion being rotatively free to follow said screw-threads and yieldingly held to its normal position at the forward end of such screw threads. 80

5. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, the screw thread of the shaft having a long lead whereby longitudinal pressure on the pinion causes rotation thereof to produce register between such pinion and engine member, and a spring rotatively free from said pinion and tending to restore the pinion to its normal position at the forward end of such screw threads. 95

6. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, and a compression spring encircling the shaft and bearing against but rotatively free from the pinion to hold the latter to its normal position at the forward end of the screw threads of such shaft, said threads being long lead whereby longitudinal pressure on the pinion causes rotation thereof to produce register between such pinion and engine member. 100

7. An engine starter drive comprising a rotatable shaft, a sleeve mounted to slide thereon and driven thereby, a driving member mounted upon the exterior of the sleeve for rotary movement therewith and for longitudinal movement thereof for engagement with a member of the engine to be started, said sleeve having at one end means for stopping the longitudinal movement of the driving member in one direction, and the driving member being normally positioned against said stop means, means for bodily shifting the sleeve and driving member longitudinally on said shaft and means for acting on the driving member to hold it in a retracted position after being disengaged from the engine member, said holding means being mounted wholly upon the sleeve. 10 15 20 25 30 35 40 45 50 55 60 65 70 75 80 85 90 95 100 105 110 115 120 125 130
- latch when the sleeve is in normal position on the shaft.
10. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, said shaft having a longitudinal slot at the rearward end of its screw threads, and a latch pivoted in such slot and adapted to engage the pinion. 10 15 20 25 30 35 40 45 50 55 60 65 70 75 80 85 90 95 100 105 110 115 120 125 130
11. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, said shaft having a longitudinal slot at the rearward end of its screw threads, and a latch pivoted in such slot and adapted to engage the pinion, the forward end of said latch tending to be held with a yielding pressure to a position coincident with the screw threads to thereby engage the pinion. 10 15 20 25 30 35 40 45 50 55 60 65 70 75 80 85 90 95 100 105 110 115 120 125 130
12. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, said shaft having a longitudinal slot at the rearward end of its screw threads, and a latch pivoted in such slot, said pinion having in its base a longitudinal slot engaged by such latch. 10 15 20 25 30 35 40 45 50 55 60 65 70 75 80 85 90 95 100 105 110 115 120 125 130
13. An engine starter drive comprising a rotatable screw shaft, a pinion threaded thereon for longitudinal movement thereon and rotary movement therewith, means for bodily shifting the shaft and its pinion in a forward longitudinal direction to cause engagement between the pinion and a member of the engine to be started, said shaft having a longitudinal slot at the rearward end of its screw threads, a latch pivoted in such slot and adapted to engage the pinion and a spring acting on the latch to hold one end thereof outside the slot to engage the pinion. 10 15 20 25 30 35 40 45 50 55 60 65 70 75 80 85 90 95 100 105 110 115 120 125 130
14. An engine starter drive including a rotatable shaft, a sleeve mounted to slide thereon and driven thereby, a driving member mounted upon the sleeve for rotary movement therewith and for longitudinal movement thereof for engagement with a member of the engine to be started, means for bodily shifting the sleeve and driving member upon the shaft, and means acting on the driving member for holding it in a retracted position with respect to the engine member and sleeve, and for releasing it, said hold- 10 15 20 25 30 35 40 45 50 55 60 65 70 75 80 85 90 95 100 105 110 115 120 125 130

ing means being mounted upon the sleeve and adapted to engage the driving member to hold it in retracted position and cooperating with the shaft for the disengagement of such means from the driving member.

15. An engine starter drive including a rotatable shaft, a sleeve mounted to slide thereon and driven thereby, a driving member mounted upon the sleeve for rotary movement therewith and for longitudinal movement thereof for engagement with a member of the engine to be started, means for bodily shifting the sleeve and driving member upon the shaft, and means acting on the driving member for holding it in a retracted position with respect to the engine member and sleeve, and for releasing it, said holding means comprising a latch pivoted upon the sleeve and cooperating with the driving member to hold it retracted and with the shaft for disengagement purposes.

16. An engine starter drive including a rotatable shaft, a sleeve mounted to slide thereon and driven thereby, a driving member mounted upon the sleeve for rotary movement therewith and for longitudinal movement thereof for engagement with a member of the engine to be started, means for bodily shifting the sleeve and driving member upon the shaft, and means acting on the driving member for holding it in a retracted position with respect to the engine member and sleeve, and for releasing it, said sleeve having a slot, and said holding means comprising a latch pivoted in its slot and cooperating with the driving member and with the shaft.

WILLIAM L. McGRATH.
